UNITED STATES PATENT OFFICE.

MALCOLM W. QUIGGLE, OF BROOKLYN, NEW YORK.

INTERNAL-COMBUSTION ENGINE.

1,082,138.

Specification of Letters Patent. Patented Dec. 23, 1913.

Application filed February 17, 1912. Serial No. 678,397.

To all whom it may concern:

Be it known that I, MALCOLM W. QUIGGLE, a citizen of the United States, residing at Brooklyn, in the county of Kings and State 5 of New York, have invented certain new and useful Improvements in Internal-Combustion Engines, of which the following is a specification.

This invention comprises improvements in 10 two cycle internal combustion engines of the kind in which each cylinder is pivoted and provided with a head at its forward end through which the piston rod extends.

The present improvements relate particu- 15 larly to means for lubricating the piston rods of such an engine.

In the accompanying drawing, which illustrates the invention, Figure 1 is a central section through the engine, taken on 20 the line of the shaft; and, Fig. 2 is a section through the engine taken transversely of the shaft and centrally of the several cylinders.

Referring to the drawing A indicates a hollow crank shaft, which is to be held stationary by suitable means, and which forms a support for the entire engine. At opposite ends of the crank *a* of said shaft are arranged ball bearings 1 and 2 in suitable 25 housings 3 and 4 to which are secured side plates 5 and 6, respectively. These side plates are preferably made of sheet steel, and they may be circular, or star shaped as shown in Fig. 1. Near the edges of these plates or disks are secured a plurality of 30 pairs of bearings 7, 8, consisting, as shown, of sleeves set into openings in the side plates or disks. The side plates are connected together at suitable intervals by a series of bolts *x*, which are preferably made tubular.

40 for the sake of lightness. Cylinder-sleeves *B* are journaled in the bearings 7 and 8 each sleeve being adapted to receive one of the cylinders *C*, *C'*, etc. Each cylinder-sleeve has a trunnion 9, fitting in a bearing 8, 45 this trunnion being preferably made hollow but closed at its inner end, and a tubular trunnion 10, projecting from the opposite side of the sleeve fits into the opposing bearing 7. The cylinders *C*, *C'*, etc., are

50 removably secured within the cylinder sleeves. In assembling the parts the forward portion of the cylinder is inserted through the sleeve until the outer end of the sleeve abuts against the first radiating flange 11, and a collar 12 is then threaded 55 onto the cylinder and abuts against the op-

posite end of the cylinder sleeve and thus the cylinder is secured within the sleeve. Each cylinder is provided with an exhaust port 13 at one side and with an inlet port 14 at its opposite side, these ports registering 60 with similar ports 13^a and 14^a in the cylinder sleeve, the ports 14 and 14^a communicating with a passageway 15 in the cylinder sleeve which passageway communicates with 65 the hollow trunnion 10, a check valve 16 being arranged between said trunnion and passageway. Each cylinder is also provided with a head 17 at its inner end which head is threaded onto the inner end of the 70 cylinder, and a pipe 18 connects the passageway 15, in the sleeve, through the cylinder head to the interior of the cylinder, the pipe 18 and passageway 15 forming a by-pass for the gas from the front to the 75 rear of the cylinder when the piston *P* is in its forward or inner position. The check valve 16 is connected to the head 17 by a flat spring 16^a which normally holds the valve 16 closed.

80 The gas or vapor for operating the engine enters through the tubular shaft *A* and said shaft has one or more ports 19 which open into an annular casing 20 journaled on the shaft and connected to the housing 85 3 for the bearings. The casing 20 has suitable packing rings for preventing the escape of gas around the shaft and it has a series of openings 21 in which are fitted pipes 22 which extend into the trunnions 10 90 of the cylinder sleeve and are fitted gas-tight therein. Thus the gas or vapor entering the shaft *A* may flow through the pipes 22 to the passageways 15, 18, and thence into the forward part of the cylinders when 95 the pistons move outwardly therein, the check valves 16 opening by reason of the suction created by the pistons. When the pistons move to the forward ends of the cylinders, the gas is compressed therein and 100 forced through the by-pass 18, 15, to the rear ends of the cylinders, where it is compressed upon the return strokes and then exploded and exhausted through the ports 13.

105 The piston rods 23 extend through the heads 17, and it is necessary to lubricate the outer surfaces of these rods and also to prevent the escape of gas around the rods. As gasolene is commonly used for the explosive 110 mixture in engines of this character, and as gasolene would cut the lubricant from the

2

piston rods, it is desirable to protect the rods, as much as possible, from direct contact with the gasolene mixture. In order to efficiently lubricate the piston rods, and to protect them from the gasoline mixture, each rod is inclosed in a sheathing consisting of a sleeve 24, integral with, or attached to, the head 17 of the cylinder and extending inwardly therefrom for a distance approximately equal to the length of the piston stroke, and a sleeve 25 of about the same length which telescopes with the sleeve 24 and has its end 25^a connected to the piston rod near the inner end of the latter. As shown in the drawing, the end 25^a of the sleeve 25 is secured between a shoulder on the rod and the piston, which is threaded onto the end of the piston rod. The sleeve 24 fits the piston rod closely and the sleeve 25, which is of larger diameter than the sleeve 24, has an integral collar 25^b, which closely fits around the sleeve 24. The two sleeves form a continuous sheathing which entirely incloses the piston rod within the cylinder, and on account of the length of the sleeve 23 and the inclosure of its upper end by the sleeve 25, there is little or no opportunity for the vapor within the cylinder to escape through the opening in the head 17 or to act upon the lubricant on the piston rod. The piston rods receive their supply of oil from the crank through central ducts 26 which lead from the inner ends of the rods to lateral outlets 26^a. The oil flowing from the crank out through these ducts lubricates the opposing surfaces of the rods and their inclosing sleeves 24. The oil is carried outward by centrifugal force from the crank to which it flows through a duct *d*, the latter extending through the shaft A to the tubular bolt 27 at the center of the crank and having branches leading to the surface of the crank pin and to the several bearings, as shown in Fig. 1. The cylinder heads 17 are dished toward the center, as shown, so as to catch any oil flying off from the parts surrounding the crank and to lead this oil inward against the sides of the piston rods, so that the rods are also lubricated by this means.

The crank is preferably made in several parts to facilitate assembling the engine and taking it apart. As shown, the crank pin comprises a cylindrical part 28, integral with the shaft, the outer surface of this part forming a bearing for the piston rods, and being suitably covered with Babbitt metal 28^a, if desired. The part 29 of the crank has a conical sleeve 30 which fits within the tapering bore of the part 28 and the parts 28 and 29 are held together by the bolt 27 which passes through the sleeve 30 and is threaded into the part 28 as shown. The parts are drawn tightly together by the bolt 65 and they are prevented from turning rela-

tively to one another by means of one or more keys 31. A collar 32 is provided upon the bolt 27 at the inner end of the tapering sleeve 30 and a recess 28^b is provided between the inner end of the sleeve 30 and the part 28 to receive this nut or collar. The purpose of the collar is to form a shoulder for forcing the tapering sleeve 30 out of the tapering bore in the part 28 when the bolt 27 is unscrewed to take the crank apart. It will be understood that the collar 32 may turn with the bolt in the recess 28^b.

The several piston rods have, connected to their inner ends, feet *e*, *f*, *g*, etc., which extend laterally to the ends of the crank pin. One of these feet, *e*, has connected thereto and midway between its ends a ring *e'* which surrounds the crank pin. Another foot, *f*, has two rings *f'*, surrounding the crank pin, at opposite sides of the ring *e'*. Another foot *g* has a pair of rings surrounding the crank pin at the sides of the rings *f'*, and, similarly, the feet *g*, *h*, and *i* have pairs of rings *g'*, *h'* and *i'*, surrounding the crank. As there is but one ring *e'* on the foot *e*, this ring is equal in width to the two rings on each of the other feet, so as to give the same bearing surface. The two rings upon each of the other feet are equidistant from the central line of the piston rods, the rings on the several feet being different distances apart so that they will rest side by side upon the crank pin. The rings are all of the same diameter and it will be noted that the foot on each piston rod bears upon the rings of all of the other rods. The bearing surfaces of the feet are preferably of hard Babbitt metal. It will also be noted that as the single ring *e'* on one foot is in line with the piston rod attached thereto and the rings on the other feet are equidistant from the centers of the rods connected to said feet, the rods will always be held in true alinement.

In the operation of the invention it will be understood that the shaft A will be secured to some suitable support, to prevent the shaft from turning. When used for a flying machine, the propeller blades will be attached, by suitable means, to the left side of the machine, in Fig. 1, and to take up the thrust of the propeller a thrust bearing 35 is provided between the crank and the housing 3. In the position shown in Figs. 1 and 2, the piston in the cylinder C' is at the point of highest compression and, assuming the engine to be rotating in the direction of the arrow, the exploded charge in the cylinders C² and C³ is forcing the pistons and piston rods against the crank; the exploded mixture is exhausting from the cylinder C⁴ and in the cylinders C⁵ and C⁶ a new charge is being compressed as the cylinders move toward the position of the cylinder C.

It will be evident that the engine is reversible and will operate in either direction according to the way in which it is started. It will also be evident that the number of cylinders may be varied. While the cylinders oscillate slightly with respect to the side plates or disks upon which they are pivoted, they always remain radial to the crank pin and do not oscillate with respect to said pin. As it is necessary to keep the engine in balance, of course a change in the number of cylinders would necessitate a change in their relative positions. As some features of the engine are suitable for four cycle engines I do not limit myself to the two-cycle construction as regards these features.

The bearings for the trunnions which support the cylinders are lubricated through tubes (not shown) attached to the side plates and extending radially from the bearings on the shaft to the trunnion bearings, so that oil from the duct *d*, after passing through the bearings on the shaft is carried out to the trunnion bearings.

What I claim is:—

1. The combination with a stationary shaft having a crank provided with oil ducts, and a plurality of cylinders pivotally mounted about the axis of said shaft, said cylinders having heads closing their forward ends, of pistons within the cylinders, piston rods extending through said heads and connected to said crank and a sheathing for each rod comprising a sleeve connected to the cylinder head through which the rod extends and a sleeve movable with the rod and telescoping with the first

mentioned sleeve, each rod being provided with an oil duct leading from its forward end to a point within the sheathing and adapted to conduct oil from the crank to the sheathing.

2. In a two-cycle internal combustion engine, a cylinder having a head closing its forward end, a piston within the cylinder and a piston rod extending through said head, said rod having an oil duct extending from its forward end to an outlet within the cylinder, in combination with a sheathing for said rod comprising a sleeve within the cylinder connected to said head and extending over the outlet of the duct, and a sleeve connected with the piston rod and telescoping with said first mentioned sleeve.

3. In a two-cycle internal combustion engine, a cylinder having a head closing its forward end, a piston within the cylinder and a piston rod extending through said head, said rod having an oil duct extending from its forward end to an outlet within the cylinder, in combination with a sheathing for said rod comprising a sleeve within the cylinder connected to said head and closely surrounding the rod, said sleeve extending over the outlet of the duct, and a sleeve connected with the rear end of the piston rod and surrounding the first mentioned sleeve and telescoping therewith.

In testimony whereof I affix my signature, in presence of two witnesses.
